UNITED STATES PATENT OFFICE

WILHELM WENTZEL, OF FRANKFORT-ON-THE-MAIN, GERMANY

DIRECTION INDICATOR FOR MOTOR CARS

Application filed April 12, 1926, Serial No. 101,451, and in Germany February 15, 1927.

This invention relates to a switch for direction indicators on motor cars, which is composed of the same number of press button switches, as there are indicating circuits 5 for the direction indicator arms. It is known, to combine such press button switches for direction indicators with a clockwork so that the press button of the switch, after being depressed, automatically returns into its inoperative position. By means of contact springs arranged in the path of the shank of the press button and consequently bridged by the press button, the circuit of the indicating arm controlled by the press button 10 switch in question is held closed during the whole period, in which the press button is moved downwards and then automatically moved back upwards, owing to the clockwork.

20 It is also known, to positively connect press buttons of a whole series of united press button switches with the aid of a common coupling element having a limited freedom of movement, in such a manner that only one of 25 all the press button switches can in any case be moved into the contact making position. A cord is often employed for such purposes as coupling element with limited freedom of movement, which cord is fixed at both ends, 30 and on which all the press buttons are suspended on rollers or the like.

According to the invention the common coupling element having a limited freedom of movement, besides being connected with the press buttons of the press button switches is also connected in a similar manner with the winding lever of a clockwork, which through the spring pressure of the clockwork holds the common cord taut by forming a 40 bend in such a manner that, when a press button is depressed and, owing to the formation of a bend at another point of the cord caused thereby, the bend around the winding lever of the clockwork is made smaller and consequently the winding lever pulled upwards and the clockwork wound. On the hand being removed from the press button in question, the winding lever, owing to the 45 spring force of the clockwork, reforms the original bend and thereby shortens the bend

formed by the press button, so that this button is returned into its initial inoperative position. With this arrangement it is possible to depress only one press button, at the same time winding the clockwork, as owing to the limited freedom of movement of the coupling element a bend can always only be present at one point.

An embodiment of the invention is illustrated by way of example in the accompanying drawing in which—

Fig. 1 shows the switch partly in longitudinal section.

Fig. 2 is a cross section through the switch.

Fig. 3 shows a switch seen from the outer side.

In the drawing A, B, C, D are the press buttons of four press button switches which are connected with a direction indicator. This combined switch is therefore in a position to open and close the four circuits of four existing indicator arms. The four circuits may for example consist of one circuit each for indicating left turning, right turning, straight on and stop. If the direction indicator has more circuits the switch therefore must have more than four press buttons, and inversely if less circuits are provided correspondingly fewer press buttons will be required. Each press button switch has two 80 blade springs c, d which are controlled by the respective press button. According to Fig. 2 each of the press buttons A, B, C, D has a cut out portion a through which a switch pin b is moved backwards and forwards at 85 right angles to the axis of the press button, as soon as the press buttons are moved up and down. The switch pin b bears against the contact spring c of two parallel contact springs c, d. As soon as the press button 90 switch having this press button A is actuated, the contact pin b will bridge the ends of the contact spring c, d owing to the depression of the press button in question. As the contact springs c and d are connected to the magnetic arrangement of the direction indicator as also to a common source of current, the indicating arm in question will be actuated by the depression of the press button A. In 95 a similar manner the springs e and f, g and 100

h, i and k will be bridged by depressing the press buttons *B, C and D* respectively.

The invention does not differ from the known devices as regards the parts hitherto described. In the known switches however each press button is in positive movable connection with a clockwork which pushes the press button back into its initial position after it has been depressed and released. The circuit in question in the direction indicator consequently remains closed during the time in which the press button is moved downwards and is then pressed back upwards by the clockwork.

15 In order to manage with only one clockwork irrespectively as to how many press button switches or press buttons *A—D* are present, the common coupling element *l* is provided, which is fixed on the casing *m* at both ends and which is wound over rollers *n* on the ends of the press buttons *A—D* and over the stationary rollers *o* in the casing *m*. This coupling element *l* must have a limited freedom of movement in such a manner that it always only allows one of the press buttons *A—D* to be moved into the switching position. The fact that this switching element *l* only possesses a limited freedom of movement presents the advantage that only a single circuit from the indicator arms can be closed, so that the errors are impossible. Other gearing parts may be employed as common coupling element.

According to the invention the coupling element *l* is wound, besides over the shiftable rollers *n* and the stationary rollers *o*, also over the roller *p* mounted on the end of the arm *q*, which is hingedly connected to the winding lever *r* of a clockwork *s*. The toothed wheels *t* in the clockwork *s* wind the spring *u* and this causes the winding arm *r* to seek to remain in its lowest position.

If the press button *a* is shifted in the manner above described into the position shown in Fig. 1, the roller *n* pulls the cord *l* into a large bend. At the same time however the arm *q* and the winding lever *r*, owing to the limited freedom of movement of the cord *l*, are moved from the position indicated in dotted lines into that shown in full lines. As soon as the press button *A* can move freely the winding lever *r* again moves into the position shown in dotted lines owing to the spring *u* and the toothed wheels *t*, and thereby lengthens the cord bend on the arm *q* with the aid of the roller *b*. In the same measure as the cord bend is enlarged around the roller *q*, the cord bend must be reduced on the roller *n* which is movable with the press button *A*. As soon as the winding lever *c* has reached its lowermost inoperative position the press button *A* will have been pushed outwards, so that, as shown in Fig. 2, the contact pin *b* slides into the cut out portion *a* and breaks

the contact between the contact springs *d* and *c*.

I claim:

In a switch for direction indicators comprising a number of circuits for the indicator arms, the combination of a plurality of press button switches corresponding to the number of circuits, press buttons controlling each of said switches, a clockwork adapted to return each of said press buttons into its inoperative position after being depressed, contact springs connected in each of said circuits, a pin on each of said switches adapted to bridge said contact springs for a specified period, a common coupling element having a limited freedom of movement arranged between all of said press-buttons adapted to allow the depression of only one of said press buttons at one time, and a lever of said clockwork positively connected to said common coupling element adapted to wind said clock work on the depression of one of said press buttons and, on the release of one of said press buttons after being depressed, adapted to pull said button into its inoperative position in the same measure as said lever is itself returned into its initial position by said clockwork.

In testimony whereof I affix my signature.

WILHELM WENTZEL.
